Primary Examiner—Ian Simmons*Assistant Examiner*—Charles D Hanson*(74) Attorney, Agent, or Firm*—Day Pitney LLP(57) **CLAIM**

The ornamental design for a hard box for media disk, as shown and described.

DESCRIPTION

FIG. 1 is a front left perspective view of a hard box for media disk showing my new design;

FIG. 2 is a right rear perspective view thereof;

FIG. 3 is an end perspective view thereof in an open position;

FIG. 4 is an interior perspective view thereof in an open position; and,

FIG. 5 is an exploded view thereof.

The broken line showing is included for the purpose of showing the boundary of what is claimed and forms no part of the claimed design.

1 Claim, 5 Drawing SheetsFIG. 1

FIG. 2

**EX PARTE
REEXAMINATION CERTIFICATE
ISSUED UNDER 35 U.S.C. 307**

AS A RESULT OF REEXAMINATION, IT HAS BEEN
DETERMINED THAT:

The patentability of one (the single claim) is confirmed.

The ornamental design for a hard box for media disk, as
shown and described.
